UNITED STATES PATENT OFFICE.

THEODORE VAN VOORST, OF TOUCHET, WASHINGTON.

FLYING MACHINE.

Application filed July 5, 1921. Serial No. 482,635.

To all whom it may concern:

Be it known that I, THEODORE VAN VOORST, a citizen of the United States, residing at Touchet, in the county of Walla 5 Walla and State of Washington, have invented certain new and useful Improvements in Flying Machines, of which the following is a specification.

This invention relates to flying machines, 10 of the helicopter variety, and its operating means.

One object of the invention is to provide means to raise a flying machine vertically and without a running start.

15 A further object of the invention is to provide means of propulsion and lifting combined into one.

A further object of the invention is to provide a means for operating the propellers 20 that will automatically maintain an even keel.

A further object is to provide a simple means of control.

25 A further object is to provide a simple and resilient landing means.

With these and other objects in view reference is now had to the accompanying drawings in which:

Fig. 1 is a side elevation of the device assembled with propeller in lifting position.

Fig. 2 is a sectional side elevation of the device with the propellers advanced for travelling.

Fig. 3 is a plan view of the device with 35 one propeller removed to show control cords.

Fig. 4 is a central sectional elevation of the machine showing walls and bottom.

Fig. 5 shows a side elevation of drum and operating worm; and

40 Fig. 6 shows the automatic means which regulates the speed of the respective propellers.

Having reference to the drawings like numerals refer to like parts throughout and the numeral (1) refers to the housing of the machine which is preferably boat shaped with its bottom (2) however, flat to provide as much room as possible for storage purposes, etc. Within the housing is the operating mechanism which is of a peculiar design essential to the proper operation of the machine. This mechanism consists of a motor (3) which is mounted in such a manner that it has a slight longitudinal movement with a variation of the housing from the horizontal, the purpose of which will be

presently explained. The mounting consists preferably of rollers (4) so that the movement of the motor is free of frictional resistance and hence will move forward or 60 backward with a very slight variation from the horizontal. Operably attached to the motor, by the chain belt (5), is the differential (6) mounted on the line shaft (7), and attached to the respective differential gears 65 (8) are discs (9) and (10) respectively, which obviously rotate with the line shaft. Loosely mounted on the line shaft are other discs (11) and (12), respectively, joined together by a yoke (13) by which means the 70 two last mentioned discs operate together and when one of these discs approach one of the first mentioned discs the other disc correspondingly recedes. The disc (11) is attached to a sleeve (14) which, as before 75 mentioned, is slidably mounted on the line shaft and the sleeve is moved longitudinally by means of the movement of the motor acting on the parallel bars (15) which are suspended from some convenient point above 80 and which are pivotally attached to the motor at the points (16).

It will now be seen that if the machine is unequally loaded or if one propeller is less 85 efficient than its fellow there will be a natural tipping of the machine from the horizontal and the motor will, by gravity, automatically move the discs (11) and (12) bringing one of them against one of the discs (9) or (10) and, as one set of discs rotate and the other set do not, a braking effect is produced on the side of the differential which is connected with the propeller most efficient; hence with this braking 90 means cooperating with the differential the 95 machine will always be maintained horizontal and on an even keel.

Propellers (17) are preferably attached to each end of the machine, and in such a manner that they may rotate therein and at the same time support the machine. This is accomplished by large thrust bearings (18) placed above and below the sill (19) through which the shaft propeller (20) passes. Below the bearings is a gear (21) which meshes 100 with the gear (22) attached to a shaft (23) which in turn is coupled to the line shaft (7) by the universal joint (24). It will here be stated that a universal joint may be substituted for the gears if desired. The propeller shaft has interposed therein a universal joint (25) which permits the propeller 105 110

to be shifted in the various positions required.

The propellers are normally positioned horizontal and parallel with the housing, as shown in Fig. 1, however to move forward the propellers are moved in the forward direction, see Fig. 2, and are given sufficient inclination to support, and at the same time propel the machine. The propellers consist 10 of a rim (32) which is supported by the spokes (33) preferably of wire, and which may be further stayed by the stiffeners (34) made of wood or other stiff metal. The propeller is of the shape of a screw the thread 15 of which makes one complete turn, and is covered by a covering member (35) of prepared cloth or other air tight material.

As above mentioned the angle of inclination of the propellers must be changed to the 20 direction of travel and I accomplish this movement of the propellers by the cross arms (36) which are loosely attached to the propeller shaft (20) that it may rotate without affecting the position of the cross arms. 25 The cross arms extend laterally from the shaft and have attached thereto cords (or wires) (37) which pass over the pulleys (38) to the drums (39), they being operated by the worm (40) and hand wheel (41); 30 thus by turning the drums the tightening of a particular cord is accomplished and the angle of the propeller changed to the required direction.

Attached to the outer wall of the housing 35 I have provided a landing means which I deem novel and which consists of wheels (42) mounted in rocker arms (43) attached pivotally to the housing at the point (44) and which are joined together by the tension 40 member (45) and the compression member (46), both of which members being so called as they carry a spring (47), which is preferably encased in a tube (48), whereby the wheels may move apart on landing and permit 45 the machine to come to rest without jar. Seats (49) may be provided forward and to the rear of the engine room (50) and windows (51) will permit the passengers to observe the scenery.

50 Having thus described my invention, I claim:—

1. In a flying machine, the combination of a housing, a self regulating operating mechanism consisting of a movable motor and a

55 differential mechanism contained within said housing, universally mounted propellers, operable by means of said mechanism, and means for changing the angle of inclination of said propellers, and a resilient landing means operably attached to said housing. 60

2. In a flying machine, the combination of a housing, a self regulating operating mechanism consisting of a movable motor, a longitudinally extending line shaft, a differential, a braking means cooperating with said 65 differential and automatically operable with the longitudinal movement of said motor, universally mounted propellers, rotatably attached to said housing, and operable by said motor, and means to change the angle 70 of inclination of said propellers.

3. In a flying machine, the combination of a boat shaped housing, a self regulating operating mechanism contained within said housing and comprising a motor, a line shaft 75 connected to said motor and extending longitudinally through said housing, and provided with a differential, and a braking means connected with said differential said braking means automatically operable by 80 the movement of said housing from the horizontal, rotatable and universally mounted propellers attached to said housing and positioned normally horizontal and parallel with said housing, means for changing the 85 angle of inclination of said propellers, means for operating said propellers from said line shaft, and a resilient landing means attached to said housing.

4. In a flying machine, a housing, propellers rotatably mounted at each end of said housing, said propellers consisting of a rim, spokes supporting said rim, and an air tight covering member covering said spokes, a cross arm loosely attached to and extending from the shaft of each of said propellers, cords attached thereto and operable with drums, means for operating said propellers and in a manner to maintain said housing horizontal, and a resilient landing means consisting of landing wheels attached to said housing by means of rocker arms, and tension and compression members attached to and cooperatively uniting said rocker arms. 90 95 100 105

In testimony whereof I affix my signature.

THEODORE VAN VOORST.
